UNITED STATES PATENT OFFICE.

ISAAC N. KNAPP, OF OMAHA, NEBRASKA, ASSIGNOR TO THE UNITED GAS IMPROVEMENT COMPANY, OF PHILADELPHIA, PENNSYLVANIA.

APPARATUS FOR TREATING ILLUMINATING-GAS.

SPECIFICATION forming part of Letters Patent No. 565,464, dated August 11, 1896.

Application filed August 8, 1895. Serial No. 558,577. (No model.)

To all whom it may concern:

Be it known that I, ISAAC N. KNAPP, a citizen of the United States, residing at the city of Omaha, in the county of Douglas and State 5 of Nebraska, have invented certain new and useful Improvements in Apparatus for Treating Illuminating-Gas, of which the following is a specification.

The principal object of my present invention is to remove or extract tar, entrained matter, and vapors, such as condense, at ordinary temperatures, from illuminating gases, such, for example, as carbureted water-gas, and to this end my invention consists of 15 the improvements hereinafter described and claimed.

In practising my invention, the temperature of the gas may be reduced to about 125°, more or less, by any appropriate means, and 20 this temperature is suitable for extracting tar and entrained matter. A considerable velocity is then imparted to the partially-cooled gas and to its tar and other entrained matter, so that they move in a predetermined direction 25 and impinge upon fixed vanes or plates which extract the tar and entrained matter, because the direction of motion of the globules and vesicles of the latter is not, by reason of their weight, readily changed, 30 and because the gas escapes from and around said plates or vanes by reason of the fact that the direction of its motion is readily changed.

The nature, characteristic features, and 35 scope of my invention will be more fully understood from the following description, taken in connection with the accompanying drawings, forming part thereof, and in which—

40 Figure 1 is a top or plan view of apparatus embodying features of my invention. Fig. 2 is a side elevational view of the same. Fig. 3 is a sectional view taken on the line 3 3 of Fig. 2, and Fig. 4 is a sectional view taken on 45 the line 4 4 of Fig. 1.

In the drawings, *a* is a casing or housing, which may be supported in any convenient manner, and which in the present instance is of cylindrical form. This casing or housing is or may be provided with hand-holes *a'*, having suitable cover-plates.

*a*² is an inlet that extends from the top of the casing or housing *a* downward through it to a point near its bottom. Beneath the bottom of the inlet *a*² is located a revoluble extracting or centrifugal discharge-wheel *b*. As illustrated in the drawings, this extracting-wheel comprises top and bottom plates, wherof the top one is provided with an opening *b'*, that communicates with the inlet *a*², and is 60 provided with radial arms *b*² and *b*³, slightly curved at their outer ends, as shown, and whereof the arms *b*² are longer than the arms *b*³.

In the exemplification of my invention 65 shown in the drawings the extracting or centrifugal wheel *b* is mounted upon a shaft *b*⁴, revolvably supported by means of the bearings *b*⁵ and by means of an adjustable step-bolt *b*⁶, carried by a yoke *b*⁷.

*b*⁸ is a gas-tight stuffing-box, and *b*⁹ a pulley to which power for rotating the extracting-wheel is applied.

c are a series of vanes or plates fixed, for example, to the casing or housing *a* and arranged around the periphery of the extracting-wheel and disposed at an inclination to the radial position, as shown.

d is a fluid offtake, and *e* is an outlet for clean gas.

The preceding description, taken in connection with the accompanying drawings, will enable the skilful mechanician to understand the construction of an apparatus embodying my improvements; consequently I shall proceed to describe the mode of operation of the same in connection with the practise of my invention in its application to the production of carbureted water-gas.

The temperature of carbureted water-gas 90 after leaving the fixing-chamber of, for instance, the well-known Lowe type of apparatus, is reduced, for example, by means of a tubular condenser or other suitable device (not shown) to 125° Fahrenheit, more or less, 95 whereupon the partially-cooled carbureted water-gas enters the inlet *a*² and passes thence through the opening *b'* into the extracting-wheel *b*, which is rapidly revolved. The globules and vesicles of tar and entrained matter, as well as the carbureted water-gas, 100 are thrown off with considerable velocity from

the periphery of the extracting or centrifugal wheel by the rapidly-moving arms b^2 and b^3 , and impinge upon the fixed vanes or plates c . These rapidly-moving globules of tar and 5 other entrained matter may not, by reason of their weight, change the direction of their motion suddenly; consequently they impinge upon and adhere to and flow or fall from the vanes or plates c , and thus escape from the 10 gas current, whereas the carbureted water-gas, being exceedingly mobile, changes the direction of its motion rapidly and escapes from between the plates or vanes into the interior of the housing or casing a , from which it is 15 passed by way of the outlet e for subsequent use, treatment, or storage. The tar and other matter extracted from the gas by the vanes or plates c may gradually accumulate at the bottom of the casing or housing, from which 20 it may be removed by way of the fluid off-take d , hand-holes a' , or otherwise, as preferred. Obviously the extracting-wheel b may be run at the proper speed for causing it not only to impart sufficient velocity to the 25 gas for causing it to be cleaned by the vanes or plates c , in the manner above set forth, but also for causing it to operate as an ex-hauster and suck gas through the inlet a^2 from the fixing-chamber and generator, so 30 that the pressure of gas from the point of generation to the extracting-wheel may be kept below the pressure of the atmosphere, which is a desirable condition under which to break up the enriching hydrocarbons by 35 heat.

If from any cause the extracting-wheel should be stopped during the period of gas-making, or if its speed should be insufficient to produce a partial vacuum, no harm can be 40 done or injury inflicted, because the openings between the arms b^2 and b^3 of the wheel constitute perfect by-pass connections through which the gas may travel.

It will be obvious to those skilled in the 45 art to which my invention relates that modifications may be made in details without departing from the spirit thereof. Hence I do not limit myself to the precise construction and arrangement of parts hereinabove set 50 forth and illustrated in the accompanying drawings; but,

Having thus described the nature and objects of my invention, what I claim as new, and desire to secure by Letters Patent, is—

1. Apparatus for extracting tar and entrained matter from illuminating-gas which consists in the combination of a centrifugal discharge-wheel, a casing arranged around the periphery of said wheel, fixed plates or vanes projecting inward from said casing and 60 arranged at inclinations to radial positions, and an outlet from the casing for the clean gas, substantially as described.

2. An apparatus for treating gas comprising the combination of, a casing or housing, 65 an inlet adapted for communication with a gas-generator and extending internally to near the bottom of said casing or housing, a revoluble wheel disposed beneath said inlet and provided with arms having openings between them that communicate with the inlet and with the interior of the housing or casing whereby velocity is imparted to the gas and its entrained matter, fixed vanes or plates interposed in the path of the rapidly- 75 moving gas and entrained matter and arranged around the periphery of said extracting-wheel and carried by said housing or casing, and clean gas and fluid off-takes 80 from said casing or housing, substantially as described.

3. An apparatus for treating gas comprising the combination of, a casing or housing provided with an inlet adapted for connection with a gas-generator and with an outlet 85 for clean gas, a centrifugal wheel having passageways communicating with the inlet and with the interior of the casing or housing and adapted to impart velocity to the gas and entrained matter, fixed vanes or plates disposed around the periphery of said wheel and in the path of the gas and its entrained matter, and a yoke-bearing and stuffing-box for revolvably supporting said wheel, substantially as described.

In testimony whereof I have hereunto signed my name.

ISAAC N. KNAPP.
